Primary Examiner — Dominic V Simone(74) *Attorney, Agent, or Firm* — Shook, Hardy & Bacon L.L.P.(57) **CLAIM**

The ornamental design for a shoe, as shown and described.

DESCRIPTION

FIG. 1 is a top plan view of a shoe showing my design; FIG. 2 is a front view thereof; FIG. 3 is a side view thereof; and, FIG. 4 is a perspective view thereof.

The even-length broken lines are directed to environment, represent unclaimed subject matter, and form no part of the claimed design.

The long-and-short broken lines form an unclaimed boundary, and form no part of the claim.
